US0D1034436S

(12) **United States Design Patent** (10) **Patent No.:** **US D1,034,436 S**
(45) **Date of Patent:** **** Jul. 9, 2024**

(54) **GENERATOR ELECTRIC**

(71) Applicant: **EcoFlow Inc.**, Shenzhen (CN)

(72) Inventors: **Weibin Gao**, Guangdong (CN); **Xi Chen**, Guangdong (CN); **Haibin Zheng**, Guangdong (CN)

(**) Term: **15 Years**

(21) Appl. No.: **35/516,990**

(22) Filed: **Jan. 11, 2023**

(80) **Hague Agreement Data**

Int. Filing Date: **Jan. 11, 2023**

Int. Reg. No.: **DM/228259**

Int. Reg. Date: **Jan. 11, 2023**

Int. Reg. Pub. Date: **Apr. 28, 2023**

(30) **Foreign Application Priority Data**

Jul. 27, 2022 (CN) 202230484912.6

(51) **LOC (14) Cl.** **13-02**

(52) **U.S. Cl.**

USPC **D13/103**

(58) **Field of Classification Search**

USPC D13/102–106, 110, 118, 119, 184, 199;
D14/253, 432, 434
CPC H01M 6/00; H01M 6/14; H01M 6/10;
H01M 10/52

See application file for complete search history.

(57) **CLAIM**

The ornamental design for a generator electric, as shown and described.

DESCRIPTION

1. Generator, electric

1.1 : Front

1.2 : Back

1.3 : Left

1.4 : Right

1.5 : Top

1.6 : Bottom

1.7 : Perspective

1.8 : Perspective

1.9 : Reference view (in state of use)

1.10 : Reference view (in state of use)

Reproduction 1.1: front view of design 1; Reproduction 1.2: back view thereof; Reproduction 1.3: left view thereof; Reproduction 1.4: right view thereof; Reproduction 1.5: top view thereof; Reproduction 1.6: bottom view thereof; Reproduction 1.7: perspective view (front, top, right side) thereof; Reproduction 1.8: perspective view (back, bottom, left side) thereof; Reproductions 1.9 and 1.10 are reference

(Continued)

views in state of use showing the handle of the article in alternative position and form no part of the claimed design.

1 Claim, 10 Drawing Sheets
